PORTRABLE DESK FOR USE ON A WHEELCHAIR

Marie Louise Moody, 4206 Homewood Court,
Riverside, Calif. 92506

Filed Mar. 16, 1972, Ser. No. 235,474

Term of patent 14 years

Int. Cl. D6—04

U.S. Cl. D6—167

Fig. 1

Fig. 2

FIG. 3

FIG. 4

FIG. 1 is a front perspective view of a portable desk for use on a wheelchair showing my new design, taken from a position above the level of the top of said desk.

FIG. 2 is a side elevation of the portable desk for use on a wheelchair, the opposite side being a mirror image thereof.

FIG. 3 is a bottom view of the portable desk for use on a wheelchair.

FIG. 4 is a rear perspective view of the portable desk for use on a wheelchair, taken from a level below the bottom of the desk.

FIG. 5 is a front perspective view of the portable desk for use on a wheelchair with its removable top removed.

FIG. 6 is a front elevation of the wheelchair desk with its removable top removed.

I claim:

The ornamental design for a portable desk for use on a wheelchair, substantially as shown and described.
